RADIO RECEIVER

Lester L. Jones, Oradell, N. J.

Application November 26, 1929, Serial No. 409,803

, 2 Claims. (Cl. 250—27)

This invention relates to radio receivers, and more particularly to a method and means for the elimination of hum and interference in power line operated radio receivers.

The primary object of the present invention is to improve the quality of the reproduction obtained from power line operated radio receivers. It is found that in spite of extreme precaution in the matter of circuit design and shielding the quality of the reception may be spoiled by disturbances, the source of which is exceedingly puzzling and little understood. The problem is further complicated by the fact that the same or similar receivers seem to behave differently in this respect when located in different places or when connected to different antenna and ground circuits. I have found that these disturbances are of two general kinds which, for convenience of reference, I shall refer to as modulation hum, and undesired interference.

Modulation hum arises only in receivers operated from alternating current power lines, and may occur at the frequency of the power supply or at double this frequency. It ordinarily is masked by the signal when a signal is being received, but becomes audible when the received carrier is not modulated. I have found that this form of disturbance, in the case of a well designed and constructed receiver, although not present when the receiver is connected to a good ground, frequently arises when the receiver is connected to a medium or poor ground. I have further found that the probable reason for this modulation hum resides in the fact that a circuit for radio frequency energy may be traced from the receiver through the power unit thereof to the power line, so that this circuit includes in series therewith the power supply rectifier of the receiver. The power line acts as a counterpoise or ground, and the rectifier in series with this ground connection varies widely in impedance at the power supply frequency, and consequently modulates the received carrier energy in the antenna circuit.

One object of the present invention is to obviate this modulation hum, and this may be done by either bypassing the power supply rectifier of the receiver with respect to radio frequency energy, or choking the radio frequency series circuit including the power supply rectifier against the flow of radio frequency energy, or both.

The other kinds of disturbance, which, for want of a better name may be called undesired interference, may occur in alternating or direct

current operated receivers, and appears in many forms. It may evidence itself by a reduction in the selectivity of the receiver, or, in the case of loop sets, by a broadening of the directivity of the loop. The interference, instead of being interfering signals, may occur in the form of static or strays, or noises originating from snap switches, sparking commutators, or other electrical machinery.

Another object of the present invention is to overcome or minimize such undesired interference as well as to eliminate modulation hum. I have found that these various disturbances may be picked up and transmitted into the receiver by the power line. I have further found that even though the set has been carefully designed and shielded against audio frequency disturbances they may appear in the set because of the fact that radio frequency energy picked up on the power line becomes modulated by these disturbances, and the receiver, while shielded against audio frequency disturbances, is not shielded against radio frequency disturbances reaching it by way of the power line. To overcome this difficulty it is merely necessary to choke the power line with respect to radio frequency energy at a point near the receiver. Shunt condensers may be additionally provided, in which case the radio frequency energy on the power line is actually filtered from the power line, preferably at a point adjacent the receiver in order to prevent further energy pickup on the line between the filter and the receiver.

Further objects of my invention are to provide suitable means for the elimination of modulation hum, to provide suitable means for the elimination of undesired interference, to devise simple and preferably common means for the simultaneous elimination, so far as may be possible, of both disturbances, and in general, to analyze and counteract the difficulties met with by the various possible combinations of a good, medium, or poor ground, and a quiet or noisy power line.

To the accomplishment of the foregoing and such other objects as will hereinafter appear, my invention consists in the method and the circuit elements and their relation one to the other as hereinafter are more particularly described in the specification and sought to be defined in the claims. The specification is accompanied by drawing in which:

Fig. 1 is a fragmentary wiring diagram illustrating one form of my invention;

Fig. 2 is a schematic diagram explanatory of features of my invention; and

Fig. 3 is a modified arrangement.

Referring to Fig. 1, there is a radio set comprising in general a radio frequency receiver 10 and a power supply unit 20 therefor. The receiver 10 consists generically of tuned circuits 12 and amplifier tubes 14, only one of each of which has been shown. The tuned circuits and amplifier tubes may be arranged in alternation, as in a tuned radio frequency receiver, or the various tuned circuits may be grouped for pre-selection and followed by an untuned or an automatically tuned amplifier. The receiver may be assumed to be shielded, as by the shield 16, and the latter is ordinarily grounded and acts as the ground of the receiver.

For a proper understanding of this invention it is important to distinguish between this ground of the receiver and what I shall term the real ground. The real ground in the present case is indicated at 18, and is electrically equivalent to one plate of a condenser, indicated at 22, representing the capacitance of the antenna 24 with respect to ground. The ground of the receiver is ordinarily considered as having the same potential as the real ground, but this is true only in the special case where the ground of the receiver is connected to the real ground by an efficient low impedance path. The ground connection ordinarily may be to a radiator, as is schematically indicated at 26, or to a gas pipe, and in such case it not infrequently happens that the ground connection 28 has considerable resistance, indicated at 30, between the ground of the receiver and the real ground. In dry country where the upper surface of the ground is lacking in moisture it may be difficult to obtain a good ground even if the physical connection between the ground of the receiver and the dry soil is made efficient, and in such case also the situation may be represented by a high resistance connected in series between the ground of the receiver and the real ground, that is, the ground which is effective with respect to the antenna.

The power supply unit 20 includes the usual power transformer 32, rectifier 34, and filter 36. The transformer 32 comprises a primary 38, a high potential secondary 40 the output of which is rectified to obtain a steady anode potential for the receiver, and a low potential secondary 42, the output of which is used for heating the cathodes of the various tubes in the receiver. It is customary to wind the transformer with the secondary 40 adjacent the primary 38, and with the secondary 42 wound outside the secondary 40, presumably because the secondary 42 consists of a few turns of coarse wire and therefore may more advantageously be wound at a larger diameter than the secondary 40, consisting of a very large number of turns of relatively expensive fine wire. For this reason there is considerable capacitance between the primary 38 and the secondary 40, indicated by the dotted condenser 44, which is not present between the primary 38 and the secondary 42.

The filter 36 consists of series chokes 46 and shunt condensers 48, in the conventional manner. This filter is designed to smooth out ripples having the relatively low power supply frequency or harmonics thereof, and condensers 48 are therefore of relatively large magnitude, say two microfarads.

It will be observed that a radio frequency

path is readily traced from the receiver ground 16 through the filter condensers 48, the power supply transformer secondary 42, the rectifier 34, the transformer secondary 40, the condenser 44, the transformer primary 38, and thence to the power line 50. The power line 50 possesses considerable distributed capacitance with respect to the real ground 18, indicated at 52, owing to its great length and distribution, and it therefore may act as a ground for the receiver, in a manner similar to a counterpoise sometimes intentionally employed as a ground.

The resulting situation may be more clearly understood by referring to the simplified schematic diagram of Fig. 2. In this diagram the antenna 24 is grounded to the real ground 18 through any suitable form of coupling impedance 25 in the receiver, and a resistance 30 caused by the receiver ground 16 being connected to only a medium or poor ground. The receiver ground 16 is also connected with the real ground 18 by another circuit in parallel with the resistance 30, this circuit consisting of a low impedance large condenser 48, a low impedance small inductance 42, a rectifier 34, a condenser 44 between the adjacent windings of a transformer primary 38 and secondary 40, and a power line 50 possessing considerable distributed capacitance 52 with respect to the real ground 18. Only one side of the rectifier circuit and one conductor of the power line have been indicated because ordinarily the capacitance 44 is so very much larger between the adjacent windings of the primary and secondary of the transformer, and therefore between the terminals connected to this side of these windings, than it is between the remote sides of the windings and the terminals connected thereto, that for all practical purposes the radio frequency series circuit may be considered as passing through only one side of the full wave rectifier and power line, just as is indicated in Fig. 2.

The rectifier 34 varies very widely in impedance in each cycle, ordinarily between infinity and say only 100 to 600 ohms. If the resistance 30 is extremely high the receiver will ground itself entirely through the power line, and it is obvious that this ground has in series therewith a variable impedance which will modulate the carrier flowing therethrough. If the resistance 30 is only moderately high, as if the receiver has a medium ground, a considerable portion of the received signal will flow through the rectifier, and the effective total impedance of the two parallel ground circuits will be similarly varied, although, of course, not to so great a magnitude as when the ground is very poor.

With the foregoing analysis of the difficulty in mind the remedies for modulation hum are relatively simple. The first is to provide a good ground. However, for the purpose of the present discussion it is assumed that the ground is either medium or poor, and as a practical matter the manufacturer of radio receivers must anticipate this condition because it very frequently arises in practice. The next general solution is to bypass the rectifier 34 with respect to radio frequencies. A radio frequency bypass condenser may be connected directly across the rectifier, but this has the disadvantage of necessitating that the condenser be capable of withstanding extremely high potentials. I prefer to bypass the rectifier 34 with a radio frequency condenser 60 connected as is indicated in Fig. 2, that is, between the ground of the receiver 16 and that

side of the power line 50 which is connected to the terminal of the transformer primary 38 nearest to the transformer secondary 40. Another general solution is to choke the radio frequency series circuit extending from the radio receiver ground 16 to the power line 50, and including the rectifier 34, with respect to radio frequencies. This is indicated by the radio frequency choke 70 connected in series with the power line 50. This solution is applicable to the case where the receiver has a medium ground, but is not desirable when the receiver has a very poor ground because the introduction of the choke 70 will impede the naturally adopted ground of the receiver. It is clear that when the receiver has a medium ground the condenser 60 and the choke 70 may both be simultaneously employed, which is of value in the event of the choke and condenser not being as efficient in their choking and bypassing functions as might be desired.

Reverting to Fig. 1, it will be observed that a condenser 60 may readily be connected between the receiver ground 16 and the terminal of the transformer primary 38 adjacent the transformer secondary 40. Also, a radio frequency choke 70 is most readily connected in series with the radio frequency circuit including the rectifier by being connected to the terminal of the power line at the receiver. The condenser 60 may be as small as 0.002 microfarads, and a magnitude of 0.005 microfarads is quite sufficient. The capacitance may be increased largely above these values, but it is desirable not to carry this increase too far, in order to avoid placing a capacitive load on the power line with respect to the power supply frequency. The choke 70 may have an impedance of the order of 10,000 ohms in the radio frequency range for which the receiver is designed.

If desired, a condenser 60' and a choke 70' may be connected in circuit as shown, making the circuit symmetrical. This avoids the necessity for knowing the internal construction of the power supply transformer, and also prevents a double frequency hum such as might occur due to passage of radio frequency currents through both rectifiers should appreciable capacitance exist between both ends of the primary and secondary of the transformer.

It may not be amiss to point out that the method of my invention, which includes bypassing the rectifier with respect to radio frequency energy, may be fulfilled by constructing the power supply transformer in a special manner so that the low potential secondary 42 thereof is wound adjacent the primary 38 and is therefore given considerable capacitance with respect to the primary, which capacitance will bypass the rectifier, and meanwhile will shield the secondary 40 from the primary.

In addition to the fact that receivers may be connected to different kinds of ground connections the receivers may be energized from different kinds of power lines. Undesired interference may be caused by transients along the power line originating with electrical machinery of various kinds, and even from switches and the like. The power line may also pick up undesired signals and transfer these through the various distributed capacitances in the receiver. Such energy not being passed through the selector of the receiver tends to reduce the selectivity thereof. In the case of a loop receiver it reduces the directivity of the loop. The precautions inher-

ently provided in even an alternating current receiver against audio frequency disturbances are not effective because the present disturbances are at radio frequency, and even audio frequency disturbances are transmitted into the receiver in the form of a modulation superimposed on some radio frequency carrier or signal picked up by the power line. To prevent this undesired interference I find it desirable to choke the power line with respect to radio frequencies at a point near the receiver. This function may be advantageously fulfilled by the chokes 70 and 70' already disclosed in Fig. 1. Also, the radio frequency shunt condensers 60 and 60' may aid in the desired elimination or filtering of radio frequency energy from the power supply energy entering the receiver. This is an additional advantage in using the symmetrical arrangement shown in Fig. 1, employing more condensers or/and chokes than would ordinarily be necessary merely for the elimination of modulation hum.

In Fig. 3 a receiver generally similar to that indicated in Fig. 1 is shown, except that this set is illustrated as having a good ground connection, as at 80. A radio frequency filter 82 may be connected in series with the power line 50 at a point at or near but not inside the receiver. It should be near the receiver to prevent energy pickup on the line between the filter and the receiver. It should be outside the shielding of the set in order to prevent the radio frequency energy from getting inside the set, for once inside there are numerous obscure paths by which the radio frequency energy may reach the detector.

Radio frequency chokes 84 and 84' alone may be used, or radio frequency shunt condensers 86 and 86' may be used, or both. The shunt capacitance, if used, is preferably provided in the form of two equal condensers grounded at their adjacent terminals for the sake of symmetry with respect to the power line and ground. The ground connection 88 should preferably be an independent connection to the real ground, as is indicated in the drawing, because if grounded to the set ground 16, first, the radio frequency energy will reach ground through the shield and a portion of the antenna to ground circuit, second, it may also reach the detector directly, and third, there is a tendency to bypass the chokes. In accordance with the present invention the filter 82 further includes radio frequency bypass condensers 90 and 90', which are grounded to the set ground 16, as shown, which incidentally prevents bypassing the chokes 84 and 84'. The condensers 90 and 90' operate in a manner analogous to the condensers 60 and 60' in Fig. 1, so that should the receiver be connected to a medium instead of the indicated good ground, modulation hum will be prevented.

It is believed that the method and circuit arrangements for the practice of my invention, and the advantages thereof, will for the most part be apparent from the foregoing description thereof. It will be appreciated that various combinations of conditions may arise, which may be counteracted in many ways. They may be briefly enumerated as follows. With a good ground and a quiet power line no difficulty arises. With a good ground and a noisy power line the power line should be choked or filtered with respect to radio frequency energy at a point adjacent the receiver. With a very poor ground and a quiet power line the power supply

rectifier should be shunted with respect to radio frequency energy. With a very poor ground and a noisy power line nothing can be done to obviate both modulation hum and undesired interference, but the rectifier may be shunted in order to eliminate modulation hum, and meanwhile improving the ground and therefore the antenna pickup. With a medium ground and a quiet power line the rectifier may be shunted with respect to radio frequency energy, thereby eliminating modulation hum and improving the ground of the receiver. With a medium ground and a noisy power line the power line is preferably choked with respect to radio frequency energy, thereby eliminating modulation hum and power line disturbances, although not improving the receiver ground. If the receiver is designed to operate from a loop within the set it is preferable to employ series chokes, and, of course, a ground other than the power line if a ground is needed, as if the loop is to be made unidirectional. The same applies to receivers using a plate antenna or other antennae within the receiver cabinet.

It will be apparent that while I have shown and described my invention in the preferred forms, many changes and modifications may be made in the method and circuits disclosed without departing from the spirit of the invention, defined in the following claims.

I claim:

1. The combination with a radio receiver energized from an alternating current power line and responsive to radio frequency energy of a desired frequency collected on a conventional antenna, said receiver including the usual grounded shielding, antenna to ground circuit, power transformer, rectifier, and filter circuits, of means to prevent modulation hum caused by the receiver being grounded through the power line.

2. The combination with a radio frequency bypass condenser connected by short direct leads between the terminal at the side of the primary of the power transformer nearest the transformer secondary and the grounded shielding of the receiver in order to form a low impedance path for the said desired radio frequency energy, said condenser being devoid of any connection to an external ground except insofar as it may be indirectly connected to said external ground through its direct connection to the shielding of the receiver.

3. The combination with a radio receiver energized from an alternating current power line and responsive to radio frequency energy of a desired frequency collected on a conventional antenna including the usual grounded shielding, antenna to ground circuit, power transformer, rectifier, and filter circuits, of means to prevent modulation hum caused by the receiver being grounded through the power line comprising a radio frequency choke for the said desired radio frequency energy connected in series with the terminal of the power line which is connected to that side of the primary of the power transformer nearest to the transformer secondary, so as to prevent radio frequency energy on the power line from reaching the receiver, and a radio frequency bypass condenser connected by short direct leads between the terminal at the side of the primary of the power transformer nearest the transformer secondary and the grounded shielding of the receiver in order to form a low impedance path for the said desired energy, said condenser being devoid of any connection to an external ground except insofar as it may be indirectly connected to said external ground through its direct connection to the shielding of the receiver.

LESTER L. JONES.
